UNITED STATES PATENT OFFICE

JAMES G. RICHEY, OF ALHAMBRA, CALIFORNIA

OIL WELL TOOL VIBRATOR

Application filed May 24, 1930. Serial No. 455,224.

My invention relates to an oil well tool vibrator and has for its principal object, the provision of relatively simple, strong and substantial means whereby rotary motion of the drill string will develop vibration in the form of vertical impulses or hammer blows that are transmitted directly to a drill or other tool that has become lodged or "stuck" in the formation at the lower end of the well hole, for the purpose of releasing said drill or tool.

Further objects of my invention are, to generally improve upon and simplify the construction of the existing forms of well tool vibrators or rotary jars, further, to provide a device of the character referred to wherein the vibratory action or impulses are produced as a result of the successive engagement and disengagement of interrupted threads on a mandrel and a bowl or sleeve that functions as a housing for said mandrel, further to provide a tool vibrating device wherein the strains developed during the use of the device are equally distributed between and throughout the mandrel and bowl or sleeve that cooperates therewith and further, to provide simple and efficient means whereby both ends of the mandrel are securely locked to the bowl or sleeve while the device and the drill string with which it is associated are being rotated during the normal operation of the drill reamer or other tool.

With the foregoing and other objects in view, my invention consists in certain novel features of construction and arrangement of parts that will hereinafter be more fully described and claimed and illustrated in the accompanying drawings, in which:

Fig. 1 is a top plan view of an oil well tool vibrator constructed in accordance with my invention.

Fig. 2 is a vertical longitudinal section taken on the line 2—2 of Fig. 1.

Fig. 3 is an elevational view of the mandrel that forms a part of my improved vibrator.

Fig. 4 is a sectional view similar to Fig. 2 and showing a modified form of the threaded connection between the mandrel and bowl.

Referring by numerals to the accompanying drawings which illustrate a practical

embodiment of my invention, 1 designates the mandrel which is cylindrical in form and on the intermediate portion of which is formed an integral circumferential rib 2.

Formed integral with the body of the 55 mandrel below the rib 2 is a plurality of interrupted threads 3 that are spaced apart a distance that is approximately equal to the width of one thread plus the width of two grooves or channels between three of the 60 threads.

Formed integral with the lower end of the body of the mandrel is a short thread 4 and the upper end of the mandrel body is externally threaded as designated by 5 in order 65 to be screw seated in the lower end of a sub or coupling that forms a part of the drill string.

Formed axially through the mandrel 70 which is a circulation duct 6 and screw-seated in the lower end of the mandrel and depending therefrom is a threaded upper end 7 of a wash pipe 8 that forms an extension of the circulation duct 6.

Enclosing the greater portion of the body 75 of the mandrel is a tubular bowl or sleeve 9 that is preferably formed in two parts to facilitate manufacture and assembly and these two parts may be permanently secured to each other at the joint 9^a by welding or 80 the meeting ends of the parts may be detachably connected by a screw joint.

Screw-seated within the upper portion of the bowl 9 and spaced apart are nuts 10 and 12, between which is arranged a compressible 85 packing ring or gasket 11 for the purpose of producing a fluid pressure tight joint between the mandrel and the upper portion of the bowl.

Formed integral with the bowl a short 90 distance below nut 12 is an internally arranged rib or flange 13 which forms an abutment or anvil, against which the rib or flange 2 is adapted to engage when the device is operated to impart vibration or hammer blows onto the lodged tool at the lower end of the drill string.

Formed integral with the bowl 9 a short 95 distance below the rib or flange 13 are internally arranged interrupted threads 14 100

that are adapted to be engaged by the threads 3 on the mandrel when the same is rotated to develop the vibratory or hammering action.

Formed within the lower portion of the bowl 9 is an internal thread 15 that is adapted to be engaged by thread 4 when the mandrel is lowered in the bowl and connected thereto, as a result of the engagement of said threads 4 with the threads 15 and that portion of the bowl below thread 15, is internally threaded for the reception of the externally threaded upper portion of a sub or coupling member 17. This sub or coupling member 17 provides means for connecting the shank of a drill or other tool, or one of the sections of the drill string may be connected thereto.

Formed through the sub or coupling member 17 is an axially disposed circulation duct 18, into which projects the lower portion of circulation tube 8 and arranged in the upper portion of the sub or coupling 17 around tube 8 is a packing ring or gasket 19 that is retained in position by a ring nut 20.

As the mandrel which moves vertically in the bowl, tube 8 slides vertically through bore 18 and the packing ring or gasket 19 provides a fluid pressure tight joint between the sub or coupling member 17 and said tube 8.

Screw-seated on the body of the mandrel 1 just below the thread 5, is a collar 21 in the underface of which is provided one or more shoulders 22, that are adapted to engage corresponding shoulders 23 that are formed on the upper end of the wall of the bowl or sleeve 9 and the threads between this collar 21 and the body of the mandrel are reversely arranged with respect to the interrupted threads 3 and 14 on the mandrel and bowl.

During drilling operations, mandrel 1 occupies a position within bowl 9 with threads 4 engaged in threads 15 and with collar 21 resting on the upper end of the bowl so that shoulders 22 engage the shoulders 23, as illustrated in Fig. 3. When so positioned the threads 3 on the mandrel are positioned below and wholly out of engagement with threads 14, but such engagement is not absolutely necessary. The drill string is now rotated in the usual manner in clockwise direction or toward the right hand and the mandrel being rigidly connected to the bowl by the engagement of the threads 15 and 4 and the engagement of the shoulders 22 and 23, the parts will rotate as one piece and the rotary motion of the upper portion of the drill string or that portion connected to the upper end of the mandrel will be directly transmitted to the tool or drill string that is connected to sub 17.

It will be noted that the interengaging threads 4 and 15 provide a strong and substantial connection between the lower por-

tion of the mandrel and the bowl and the shoulders 22 and 23 provide a substantial driving connection between the upper portions of the mandrel and bowl and thus the torque or driving strains that are transmitted from the mandrel to the bowl are equalized and uniformly distributed between the two parts.

Inasmuch as the collar 21 is mounted on a left hand thread on the upper end of the mandrel it will not back off or unscrew while the drill string is being rotated during drilling operation.

When the tool at the lower end of the drill string becomes wedged or anchored in the formation at the bottom of the well hole and it is desired to vibrate said tool for the purpose of loosening same, the drill string is reversely rotated relative to the direction in which it was rotated during drilling operations and such action disengages thread 4 from thread 15 and simultaneously disengages shoulders 22 from shoulders 23.

This reverse rotation continues until hammer 2 engages anvil 13 and after such engagement the mandrel is again rotated toward the right hand as while drilling and such action effects an engagement of the threads 3 on the mandrel with the threads 14 on the bowl. As such rotation of the mandrel takes place the threads 3 on the mandrel will, during each complete rotation thereof, ride off the threads 14 on the bowl and due to the spaced arrangement of the threads 3 and 14, the mandrel will move upward with a quick motion due to the upward pull or strains on the mandrel and as a result the upper face of ring or flange 2 will strike against the underface of ring or flange 13, thereby imparting vibration in the form of hammer blows that are delivered in an upward direction to the bowl and such impulses are transmitted to the tool that is connected to said bowl.

It will be understood that while the mandrel is being rotated to effect an engagement of the threads 3 with the threads 14, the upper portion of the drill string to which the mandrel is connected is under strains developed by upward pull on the drill string and it necessarily follows that when the threads 3 ride off the threads 14 the mandrel will move upward under the influence of the pull or strains impressed on said mandrel so as to bring about the vibration or hammer blows as described.

Thus during the operation of my improved device to produce vibratory hammering action on the bowl and the parts connected thereto, the mandrel is continuously rotated and it is not necessary to reverse the rotation of the mandrel or to stop the same in order to effect a reengagement of the threads or to produce pulling strains in the drill

string and the mandrel that is connected thereto.

Obviously the interengaging threads 3 and 14 may be formed so that the drill string may be rotated in either direction, that is, toward the right hand or toward the left hand and it necessarily follows that the threads 4 and 15 and the engaging shoulders 22 and 23 must be arranged to correspond with the right or left hand threads on the mandrel and bowl.

It will be noted that in my improved tool the interengaging threads 3 and 14 that are effective in producing the vibration as the mandrel is rotated extend around practically the entire circumference of the mandrel and likewise approximately the entire circumference of the inner face of the bowl so that the pulling strings when the threads are engaged are equally distributed around the circumference of the mandrel and around the wall of the bowl.

In the construction illustrated in Figs. 1, 2 and 3, I have shown one set of the interengaging threads 3 and 14 with the openings or cut-away portions of said threads on one side of the mandrel. In order to equalize and distribute the strains developed by the interengaging threads while the tool is being vibrated, two or more sets of interengaging threads may be provided on the mandrel and bowl, as illustrated in Fig. 4 and where such construction is employed the openings between the threads of the two sets are arranged on opposite sides of the mandrel.

In order to reduce friction between the mandrel and bowl while the same is in operation the spaces or chambers between said parts may be packed with grease.

In the event that it is desired to impart vibration to the bowl in a downward direction, the drill pipe or string to which the mandrel is connected is reversely rotated or rotated toward the lefthand (assuming that the interengaging threads 3 and 14 are righthand threads) and during which reverse rotation upward pull or tension is imparted to the mandrel and the drill string to which the same is connected.

When the upper face of the rib 2 that functions as a hammer engages the underface of the anvil 13, the upward strains or tension on the mandrel and drill string are relieved, but the reverse rotation thereof is continued. As a result the threads on the mandrel will ride up the threads on the bowl and when the ends of these threads pass each other the mandrel will drop the distance between the threads and the threads on the mandrel will strike against the threads on the bowl so as to hammer or vibrate the same downwardly.

Thus it will be seen that I have provided a well drilling tool vibrator that is relatively simple in construction, inexpensive of manu-

facture and very effective in performing the functions for which it is intended.

The device is provided with a circulation opening and simple and effective packing means are provided at both ends of the device for producing fluid pressure tight joints between the mandrel and bowl.

It will be understood that minor changes in the size, form and construction of the various parts of my improved oil well tool vibrator may be made and substituted for those herein shown and described without departing from the spirit of my invention, the scope of which is set forth in the appended claims.

I claim as my invention:

1. In an oil well tool vibrator, a mandrel, a bowl in which said mandrel is positioned, cooperating interrupted threads on said mandrel and bowl which threads extend around the mandrel and bowl respectively for more than three-quarters of the circumference thereof, a shoulder on the interior of the bowl, and a shoulder on said mandrel.

2. In an oil well tool vibrator, a mandrel, a bowl in which said mandrel is positioned, cooperating interrupted threads on said mandrel, and bowl which threads extend around the mandrel and bowl respectively for more than three-quarters of the circumference thereof, a shoulder on the interior of the bowl, a shoulder on said mandrel and interengaging threads on the lower portions of said mandrel and bowl.

3. In an oil well tool vibrator, a mandrel, a bowl in which said mandrel is positioned, cooperating interrupted threads on said mandrel and bowl which threads extend around the mandrel and bowl respectively for more than three-quarters of the circumference thereof, a shoulder on the interior of the bowl, a shoulder on said mandrel, interengaging threads on the lower portions of said mandrel and bowl and shoulders on the upper portions of the mandrel and bowl for engaging one another when the threaded lower end of the mandrel is screwed into the threaded lower portion of the bowl.

4. In an oil well tool vibrator, a mandrel, a bowl in which said mandrel is positioned, cooperating interrupted threads on said mandrel and bowl which threads extend around the mandrel and bowl respectively for more than three-quarters of the circumference thereof, a shoulder on the interior of the bowl, a shoulder on said mandrel and there being an axially disposed circulation duct formed through said mandrel.

5. In an oil well tool vibrator, a mandrel, a bowl in which said mandrel is positioned, cooperating interrupted threads on said mandrel and bowl which threads extend around the mandrel and bowl respectively for more than three-quarters of the circumference thereof, a shoulder on the interior of the bowl,

a shoulder on said mandrel, there being an axially disposed circulation duct formed through said mandrel and a tube seated in the lower end of said mandrel and extending downwardly through the lower portion of said bowl.

6. In an oil well tool vibrator, a bowl formed in two parts that are rigidly connected to each other, a mandrel within said bowl, a shoulder formed within the bowl, a shoulder formed on the mandrel, which last mentioned shoulder is adapted to engage the shoulder in the bowl when the mandrel is moved upward through the bowl and cooperating interrupted threads on said mandrel and bowl which threads extend around the mandrel and bowl respectively for more than three-quarters of the circumference thereof.

7. In an oil well tool vibrator, a bowl formed in two parts that are rigidly connected to each other, a mandrel within said bowl, a shoulder formed within the bowl, a shoulder formed on the mandrel, which last mentioned shoulder is adapted to engage the shoulder in the bowl when the mandrel is moved upward through the bowl, cooperating interrupted threads on said mandrel and bowl which threads extend around the mandrel and bowl respectively for more than three-quarters of the circumference thereof and cooperating means on said mandrel and bowl for securing both ends of said mandrel to said bowl when said mandrel is at its lowermost position within the bowl.

8. In an oil well tool vibrator, a bowl, a mandrel positioned therein, a hammering shoulder on the mandrel, an anvil shoulder on said bowl, cooperating interrupted threads on said mandrel and bowl and which threads are spaced apart a distance approximately equal to the width of three threads and extending around said mandrel and bowl respectively for more than three-quarters of the circumference thereof.

9. In an oil well tool vibrator, a bowl, a mandrel arranged within said bowl, a hammering shoulder on said mandrel, an anvil shoulder on said bowl and a plurality of cooperating interrupted threads on said mandrel and bowl which threads extend around the mandrel and bowl respectively for more than three-quarters of the circumference thereof, the openings between the ends of one set of threads being diametrically arranged relative to the openings between the ends of the other set of threads.

10. In an oil well tool vibrator, a bowl, a mandrel arranged within said bowl, a hammering shoulder on said mandrel, an anvil shoulder on said bowl, a plurality of cooperating interrupted threads on said mandrel and bowl which threads extend around the mandrel and bowl respectively for more than three-quarters of the circumference thereof, the openings between

the ends of one set of threads being diametrically arranged relative to the openings between the ends of the other set of threads and cooperating means on said mandrel and bowl for securing both ends of the mandrel to said bowl when said mandrel is at its lowermost position within the bowl.

11. In an oil well tool vibrator, a mandrel, a bowl in which said mandrel is mounted for operation and cooperating means on said bowl and mandrel for converting continuous rotary motion of the mandrel into vibratory motion and imparting said vibratory motion to said bowl which cooperating means comprises interengaging threads that extend around the mandrel and bowl for more than three-quarters of their circumference.

12. In an oil well tool vibrator, a mandrel, a bowl within which said mandrel is arranged for operation and cooperating means on said bowl and mandrel whereby continuous rotation of the mandrel while under tension develops vibratory motion and transmits same to the bowl which cooperating means comprises interengaging threads that extend around the mandrel and bowl for more than three-quarters of their circumference.

13. In an oil well vibrator, a mandrel, bowl within which said mandrel is arranged for operation, a shoulder within the bowl, a shoulder on said mandrel, which last mentioned shoulder is adapted to engage the shoulder on the bowl and cooperating means on said mandrel and bowl whereby continuous rotary motion of the mandrel in one direction while under tension, moves the mandrel lengthwise through the bowl and then releases said mandrel to permit the shoulder thereon to engage the shoulder on said bowl which cooperating means comprises interengaging threads that extend around the mandrel and bowl for more than three-quarters of their circumference.

14. In an oil well tool vibrator, a mandrel, a bowl within which said mandrel is arranged for operation, cooperating means on said bowl and mandrel whereby continuous rotation of the mandrel, while under tension, develops vibratory motion and transmits same to the bowl, said cooperating means comprising interengaging threads on the mandrel and bowl and which extend around said mandrel and bowl for more than three-quarters of their circumference and shoulders formed on the upper portion of the bowl and mandrel, which shoulders provide a driving engagement between the mandrel and bowl when said mandrel is at the lower limit of its movement within the bowl.

15. In an oil well tool vibrator, a mandrel, a bowl within which said mandrel is arranged for operation, cooperating means on said bowl and mandrel whereby continuous rotation of the mandrel while under tension develops vibratory motion and trans-

mits same to the bowl, said cooperating means comprising interengaging threads on the mandrel and bowl and which extend around said mandrel and bowl for more than three-quarters of their circumference and interengaging means between the lower portion of the mandrel and bowl for providing a driving engagement between the mandrel and bowl when said mandrel is at the lower limit of its movement in said bowl.

16. In an oil well tool vibrator, a mandrel, a bowl within which said mandrel is arranged for operation, cooperating means on said bowl and mandrel whereby continuous rotation of the mandrel, while under tension, develops vibratory motion and transmits same to the bowl said cooperating means comprising interengaging threads on the mandrel and bowl and which extend around said mandrel and bowl for more than three-quarters of their circumference, packing between the upper portion of the bowl and said mandrel, said mandrel having an axially disposed circulation duct, a tube depending from said mandrel and forming an extension of the circulation duct therethrough and packing between said tube and the lower portion of said bowl.

17. In an oil well tool vibrator, a mandrel, a bowl within which said mandrel is arranged for operation, cooperating means on said bowl and mandrel whereby continuous rotation of the mandrel, while under tension, develops vibratory motion and transmits same to the bowl said cooperating means comprising interengaging threads on the mandrel and bowl and which extend around said mandrel and bowl for more than three-quarters of their circumference, packing between the upper portion of the bowl and said mandrel, said mandrel having an axially disposed circulation duct, a tube depending from said mandrel and forming an extension of the circulation duct therethrough, a sub located in the lower end of the bowl and packing between said sub and circulation tube.

18. In an oil well tool vibrator, a mandrel, a bowl in which said mandrel is positioned, cooperating interrupted threads on said mandrel and bowl, which threads extend around said mandrel and bowl respectively for more than three quarters of the circumference thereof and said threads being spaced apart a distance substantially greater than the width of a single thread.

In testimony whereof I affix my signature.
JAMES G. RICHEY.
